PULSE-TRANSMISSION SYSTEM

Our present invention relates to a telecommunication system having means for transmitting short input signals, such as counting pulses used in the determination of toll charges, over a line capable of transmitting direct-current voltages of either polarity.

D.C. pulses are commonly used in transmitting numerical information over relatively short lines, either by superimposing a continuous voltage upon voice currents or other A.C. message signals or by briefly interrupting the line loop to which a steady potential is being applied; in a telephone system, the latter mode of signaling is suitable only after termination of conversation in order not to create objectionable interferences with the voice-frequency currents. When pulsing is required during message transmission, the suppression of transients associated therewith is difficult; in the case of toll signals the situation is aggravated by the fact that, the longer the line, the higher (as a rule) the pulse rate so that harmonics within the voice-frequency band may have appreciable amplitudes.

Generally, the problem of noise suppression in conjunction with superimposed D.C. pulses has several aspects, i.e.:

- a. the need for a relatively large pulse amplitude exceeding the permissible noise level;
- b. the steepness of the pulse flanks which generate transients at high frequencies which are capacitively transmissible to adjoining lines or other parts of the system;
- c. arcing, chattering of relays and similar phenomena giving rise to parasitic signals.

The principal object of our present invention, therefore, is to provide means in a telecommunication system for eliminating or at least mitigating the above-enumerated drawbacks.

More specifically, our invention aims at avoiding the need for high-amplitude current pulses and reducing the number of voltage jumps in the transmission of a given train of input pulses, advantageously with simultaneous lessening of the voltage gradient at the leading and trailing edges.

It is also an object of this invention to provide receiving circuitry eliminating the need for conventional pulse-repeating relays directly connected across the line.

These objects are realized, pursuant to the present invention, by the provision of switch-over means at a first or transmitting station of a telecommunication (e.g. telephone or teleprinter) system for alternately connecting two voltage sources, of opposite polarities, to the line; upon the occurrence of any input pulse to be transmitted, the polarity of the line voltage so applied is reversed. At a second or receiving station, a detector responds to the polarity reversals to trigger a pulse-generating circuit so as to produce an output pulse upon each change in polarity, these output pulses following one another at a rate substantially identical with that of the input pulses giving rise to the polarity reversals at the transmitting station.

In this way, only a single voltage edge is transmitted over the line for each signal pulse in lieu of the two steep flanks corresponding to the leading and trailing edges of the pulses appearing on the line in conventional systems. As the recurrence rate of these voltage jumps is considerably reduced, the risk of harmful resonances within the band of signal frequencies is minimized.

At the receiving end, the polarity reversals are detected by a rectification network in the input of an amplifier, preferably in the form of one or more transistor stages, or of a pair of such amplifiers, e.g. two transistors of opposite conductivity types. The rectification network, according to a more specific feature of our invention, has two parallel branches including oppositely poled diodes which pass alternate polarity reversals to respective input electrodes (such as base and emitter) of the common amplifier or to the two oppositely conductive amplifiers; it is also possible to have a single amplifier connected for substantial saturation and cutoff, respectively, by the alternating D.C. line voltages and to differentiate the resulting square waves in the amplifier output to convert their leading and trailing edges into individual output pulses. In either case

we prefer to include one or more capacitors in the rectification network; the latter may comprise one or more diodes allowing the buildup of charges of only one polarity on each of these capacitors. Conventional threshold devices, such as Zener diodes, may be used to limit the magnitude of the charge. The detector circuit may also include means for sharpening the transmitted voltage steps. The above and other features of our invention will be described in greater detail with reference to the accompanying drawing in which:

FIG. 1 is a circuit diagram showing a communication system with two stations equipped with signal-transmitting and signal-receiving means according to the invention;

FIG. 2 is a set of graphs related to the operation of the system of FIG. 1;

FIGS. 3 and 4 are circuit diagrams showing modifications of the receiving equipment in the system of FIG. 1; and

FIG. 5 is a set of graphs relating to the operation of the receiver of FIG. 4. In FIG. 1 we have shown a telecommunication system comprising a first subscriber line L_1 , a trunk line L and a second subscriber line L_2 coupled for alternating-current transmission by repeaters (illustrated as transformers) Ts_1 and Ts_2 at a first and a second station with transmitting and receiving central-office equipment Tr and Rec . Trunk line L comprises a pair of continuously conductive wires $1a$, $1b$ separated by condensers C_1 , C_{II} . Wire $1a$ may be grounded or replaced by ground; wire $1b$ serves for the transmission of D.C. signals as described hereinafter.

The transmitter Tr includes two sources $-E$, $+E$ of negative and positive voltage. A switch s , shown as the armature of a relay S symbolizing both electromagnetic and electronic switch-over means, is connected to an input lead d terminating substantially at the electrical midpoint of the secondary of repeaters Ts_1 (with an assumed direction of transmission from line L_1 to line L_2); an output lead e is similarly connected to the primary of repeater Ts_2 . It will be understood that the roles of these leads may be interchanged if the call proceeds from line Ts_2 to line Ts_1 , with duplication of equipment Tr and Rec at both stations for selective connection to the line by switches not shown. Lead d is grounded for alternating current through a condenser C and is also connected to ground through two Zener diodes Z_1 , Z_2 arranged back-to-back. Relay S responds to current from an output electrode of a flip-flop F which is alternately set and reset by successive input pulses Ip from a pulse generator P ; the latter may be controlled, in a manner well known per se, to emit pulses at a rate dependent upon the distance between the two exchanges serving the lines L_1 and L_2 . This rate may be determined, for example, by dialing pulses originating with the calling subscriber on line L_1 which select the trunk L and, beyond it, the local line L_2 and the desired subscriber. Resistors R_1 and R_2 connect sources $-E$ and $+E$ to respective contacts alternately engageable by switch armature s .

At the receiver Rec , lead e conducts the signaling voltages from conductor $1b$ through a resistor R_3 to a rectification network with two parallel branches including respective diodes D_1 and D_2 in series with a pair of condensers C_1 and C_2 as well as further diodes D_4 and D_7 , the two diodes D_1 , D_4 or D_2 , D_7 of each branch being poled in the same sense and reversed with reference to the diodes of the other branch. A rectifying shunt arm across diodes D_1 and D_2 , connected between the junctions of these diodes with their associated condensers, includes a half-wave rectifier or diode D_3 in series with a threshold circuit which consists of a Zener diode Z bridged by a resistor R_4 ; the magnitude of this resistor is large compared with the breakdown resistance of Zener diode Z which lies in bucking relationship with diode D_3 . During long intervals between polarity changes, resistor R_4 substantially equalizes the potentials on condensers C_1 and C_2 .

A transistor T , here shown to be of the NPN type, has its base connected through a diode D_5 to the junction of condenser C_1 with diode D_4 , this junction being also returned to ground through a resistor R_5 which helps differentiate the charging current of this condenser. In analogous manner, the

emitter of transistor T is connected to the junction of condenser C₂ with diode D₇ by way of a diode D₆, that junction being also grounded through a differentiating resistor R₆. An output resistor R₇ is connected to the collector of the transistor which is tied to an input terminal of a pulse shaper T_m producing a train of output pulses I_q on an outgoing lead u.

The operation of the system of FIG. 1 will now be described with reference to FIG. 2. Graph (a) of this FIG. shows the train of input pulses I_p whose cadence may be constant or variable. Graph (b) illustrates the corresponding square wave W generated by the alternate energization and deenergization of relay S as the flip-flop F is alternately set and reset by successive pulses I_p, the switchover from voltage +E to voltage -E or vice versa occurring at some point (not critical) during the existence of each input pulse. Positive voltage +E on lead e (FIG. 1) causes current flow through diodes D₂ and D₇ to charge the condenser C₂ until the potential difference across Zener diode Z, in the forward direction of series diode D₃, reaches the breakdown level whereupon condenser C₁ begins to charge in the same sense, the charging current passing partly through resistor R₅ (giving rise to a positive voltage pulse thereacross) and partly through the input circuit of transistor T by way of diodes D₅, D₆ and D₇ in series. Transistor T is thus turned on and generates a voltage drop across its output resistor R₇ in the form of a brief trigger pulse P as shown in graph (c) of FIG. 2. Upon reversal of the polarity on lead e, the positive charge on condenser C₂ is trapped and current now flows through diode D₄, condenser C₁, diode D₂ and resistor R₃ to negative potential until the charge of condenser C₁ has gone sufficiently negative to cause another breakdown of Zener diode Z; current now flows through condenser C₂ via diodes D₄ and D₅, the input of transistor T, diodes D₆ and D₃, Zener diode Z and diode D₁ to generate another trigger pulse P across output resistor R₇. Pulse shaper T_m converts these pulses P into output pulses I_q, graph (d), of desired amplitude and width, e.g. commensurate with the original input pulses I_p from which they are but slightly staggered in time.

The receiver Rec' of FIG. 3 comprises, in series with a lead e' and a resistor R₃', a rectification network whose parallel branches include respective diodes D₁', D₂' and condensers C₁', C₂'; the condensers are shunted by individual diodes D₄', D₇' so as to be capable of acquiring only negative and positive charges, respectively. The emitter of an NPN transistor T₁' is connected to the junction of diode D₁' with condenser C₁', whereas the emitter of a PNP transistor T₂' is analogously connected to the junction of diode D₂' and condenser C₂'. The bases of the two transistors are connected to ground through respective resistors R₅', R₆' and a common integrating network consisting of a condenser C₃' and a resistor R₄' in parallel, this network serving to shunt out voice-frequency signals and spurious oscillations. Two output resistors R₇' and R₈', respectively connected to the collectors of transistors T₁' and T₂', generate alternate trigger pulses for a pulse shaper T_m' designed to convert pulses of either polarity into unipolar (e.g. positive) output pulses I_q (FIGS. 1 and 2) of desired width and height on an outgoing lead u'.

The operation of the receiver Rec' of FIG. 3 differs from that of receiver Rec (FIG. 1) in that negative polarity on lead e' energizes the transistor T₁' whereas positive polarity energizes the transistor T₂'. The output leads of these transistors, beyond their junctions with resistors R₇' and R₈', may include further capacitors (not shown), as part of pulse shaper T_m', as well as rectifiers to derive spikes similar to pulses P (FIG. 2) from the leading or trailing edges of the voltage pulses developed across these resistors, generally in the manner described hereinafter with reference to FIGS. 4 and 5.

FIG. 4 shows a further receiver Rec'' comprising, in essence, a detector resembling the right-hand half of the circuit of FIG. 3. Thus, a lead e'' is connected through a resistor R₃'' to a rectification network including a condenser C₁'' and a diode D₄'' in parallel, their junction being tied to the base of

an NPN transistor stage T₁'' whose emitter receives a suitable biasing voltage from a voltage divider R₉'', R₁₀'' connected between ground and a point of negative potential. The collector of stage T₁'' is connected to the base of a PNP transistor stage T₂'' with grounded emitter and with a collector connected to negative voltage through a load resistor R₁₁''. The latter collector works through an output capacitor C_u into a pulse shaper T_m'' having an outgoing lead u''.

Graph (a) of FIG. 5 shows a composite wave W'' which includes A.C. message signals together with superimposed D.C. voltages of alternate polarity. The A.C. component is filtered out by the condenser C₁'' so that transistor T₁'' sees only a positive voltage step V'' whenever the DC signaling voltage is of that polarity; negative voltages are suppressed by the rectifier D₄''. The flanks f₁, f₂ of the DC signal have a relatively gentle slope, owing to the provision of reactances such as condenser C (FIG. 1) in the transmitter; this reduces the accompanying transients. Transistor stage T₁'' may not be driven to full saturation and cutoff, respectively, by the upper and lower signal levels of graph (a), FIG. 5; the second stage T₂'' however, responds with the sharp voltage step V'' across resistor R₁₁''. Condenser C_u, together with this resistor, differentiates the leading and trailing edges of this voltage step so as to give rise to consecutive spikes Sp₁, Sp₂ of positive and negative polarity, respectively, to which the pulse shaper T_m'' invariably responds by generating the output pulse I_q, graph (d), on lead u''.

The pulse shaper T_m' of FIG. 3 may also include second-stage transistors (e.g. of PNP type for transistor T₁' and of NPN type for transistor T₂') to sharpen the output pulses developed across resistors R₇' and R₈' prior to differentiation by R/C networks similar to circuit R₁₁''', C_u.

We claim:

1. In a communication system provided with a transmission line capable of transmitting D.C. signals from a first station to a second station, the combination therewith of:

40 a source of positive voltage and a source of negative voltage at said first station;

45 switcher means at said first station for alternately connecting said sources to a conductor of said line; a generator of input pulses at said first station connected to operate said switcher means once per input pulse whereby each input pulse gives rise to a polarity reversal on said conductor;

50 detector means at said second station connected to said line and responsive to polarity reversals on said conductor; and circuit means connected to said detector means at said second station for converting each polarity reversal on said conductor into a respective output pulse.

55 2. The combination defined in claim 1 wherein said detector means comprises amplifier means provided with an input circuit including capacitive means connected to said conductor.

3. The combination defined in claim 2 wherein said input circuit includes a rectification network with two parallel branches and oppositely poled diodes respectively connected in said branches.

60 4. The combination defined in claim 3 wherein said capacitive means includes a pair of condensers respectively connected in said branches in series with said diodes.

5. The combination defined in claim 4 wherein said network is provided with a rectifying shunt arm connected between respective junctions of said condensers and said diodes, said amplifier means comprising a transistor with a base and an emitter respectively connected to said branches for energization from said conductor via said diodes and condensers thereof.

65 6. The combination defined in claim 5 wherein said shunt arm includes a half-wave rectifier, a Zener diode in series with said rectifier and an equalizing resistor in parallel with said Zener diode, said resistor being of large magnitude compared with the breakdown resistance of said Zener diode.

7. The combination defined in claim 4 wherein said network includes two further diodes respectively connected across said condensers for preventing charge inversions thereon.

8. The combination defined in claim 4 wherein said amplifier means comprises a pair of transistors of opposite conductivity types respectively connected across said condensers.

9. The combination defined in claim 2 wherein said amplifier means is connected for substantial saturation and cutoff, respectively, by potentials of opposite polarities on said

capacitive means, said circuit means including a differentiation circuit responsive to leading and trailing edges of square waves generated by said amplifier means upon alternate saturation and cutoff.

5 10. The combination defined in claim 2 wherein said amplifier means comprises two transistor stages of opposite conductivity types.
